Charles Turner Brown,
ATTORNEY

UNITED STATES PATENT OFFICE.

ISAAC S. DEMENT, OF ST. NICHOLAS, FLORIDA.

PRINTING-WHEEL.

956,891.

Specification of Letters Patent.

Patented May 3, 1910.

Application filed August 23, 1909. Serial No. 514,210.

To all whom it may concern:

Be it known that I, ISAAC S. DEMENT, a citizen of the United States, and a resident of St. Nicholas, in the county of Duval and State of Florida, have invented certain new and useful Improvements in Printing-Wheels, of which the following, when taken in connection with the drawing accompanying and forming a part hereof, is a full and 10 complete description, sufficient to enable those skilled in the art to which it pertains to understand, make, and use the same.

This invention relates to printing wheels used in registering, dating, numbering, adding and other like machines.

The object of the invention is to obtain, at small cost, a printing wheel (provided with characters on the periphery thereof) which will be light in weight and durable; 20 and also to obtain a printing wheel, which will, when made in large quantities, be accurately constructed, so that one thereof will be the duplicate of the others.

In the drawing referred to I have illustrated a device embodying my invention provided with numerals from one to zero on the periphery thereof and in which drawing—

Figure 1 is the front view of a blank from 30 which one member of the device is obtained. Fig. 2 is an edge elevation of the blank illustrated in Fig. 1. Fig. 3 is a front view of the member of the device which is obtained from the blank illustrated in Figs. 1 and 2. 35 Fig. 4 is a front view of a blank from which an additional member of the device embodying the invention is obtained. Fig. 5 is a front view of the member obtained from the blank illustrated in Fig. 4, joined to the 40 member illustrated in Fig. 3. Fig. 6 is a vertical sectional view of a device embodying the invention on lines 6—6 of Fig. 5, viewed in the direction indicated by the arrows, and Fig. 7 is a perspective of a 45 comb provided with fingers, by means of which fingers a plurality of the devices embodying this invention may be actuated in a determined order.

A reference letter applied to indicate a 50 given part is used to designate such part throughout the several figures of the drawing, wherever the same appears.

A is a blank provided with the central aperture a, a', and with the peripheral lugs or ears B. As many lugs or ears B are made 55 to blank A as are desired. Usually the number thereof corresponds with the number of characters on the periphery of the device.

1, 2, 3, 4, 5, 6, 7, 8, 9, 0, (Fig. 1), are the 60 characters which appear on the periphery of the device in the construction illustrated in the drawing. These numerals are shown as raised, as appears from the parts lettered X, in Figs. 2, 3, 5 and 6 of the drawing. The broken lines C—C, Fig. 1 indicate the 65 lines on which the several ears B are bent to lie at substantially right angles to the remainder of the blank A in the complete device.

D, Fig. 4, is a blank from which one member 70 of the device is obtained.

d is an aperture in blank D and d' is a tongue made in the cutting out of the aperture in the blank.

E is a notch or recess on the peripheral 75 edge of blank D.

C' is a broken line indicating the line on 80 which the part B' of the blank D is bent to form a cylindrical body. The cylindrical body formed by bending part B' on line C' is provided with a notch or recess (by means of recess E), and such cylindrical body is made of a suitable diameter so that it may be pressed in, to fit closely to the several ears B, after such ears have been formed into the shape illustrated in Figs. 3, 5 and 6 of the drawing. At the same time part B' is formed up on line C' the tongue d' is bent on line b' to substantially right angles with the plane in which the part of the blank D 85 is between the lines C' and the aperture d, lies.

When the member obtained from the blank D is forced into its determined position relative to the member obtained from the blank A the end of the tongue d', is 90 contained in part a' of aperture a, a', of blank A; and the recess E of blank D is between a determined pair of the ears B, B.

F, Fig. 7, is a comb provided with fingers 100 f. Comb F is designed to be moved reciprocally and actuate one or a plurality of the devices embodying this invention, in a determined manner. With this in view the

ends f' , f'' , f''' , f'''' , of the fingers f are shaped so that one thereof may rest on the periphery of one of the plurality of devices which are rotatably mounted on shaft G . The recess 5 E is made so that when the device is actuated by one of the fingers of the comb illustrated in Fig. 7 and the next adjacent wheel is also to be actuated the finger actuating the wheel of highest denomination is the shortest operative finger, and rests on the part B' between the parts B ; and the fingers actuating the wheel of lower denomination fall into recess E , that is, the shortest finger of the comb which at any given time actuates one 10 of the devices will rest on the periphery of such device, and all of the fingers of the comb which are longer will enter the recesses of the wheels actuated thereby and move such wheels to bring the zero thereof into 15 the printing line. The recess E therefore corresponds with what is termed the deep notch in the ordinary counting wheels of a series which are actuated by the fingers of a comb.

20 25 The members obtained from blanks A and D may be joined permanently by forcing them together as hereinbefore described, when made of sheet steel or other like metal, and, in addition thereto, when such members 30 are made of sheet brass or other like metal, they may be soldered or brazed together.

Having thus described my invention what I claim as new and desire to secure by Letters Patent is:—

35 1. In a printing wheel, a sheet metal member provided with a body portion, and provided with a plurality of lugs arranged in planes which are concentric to the axis of the wheel, in combination with an 40 additional member joined to the first named member, said additional member provided with an annular flange having an aperture therethrough, said members respectively provided with apertures concentric to said 45 axis.

2. In a printing wheel, a sheet metal member provided with a body portion, and provided with a plurality of lugs arranged in planes which are concentric to the axis of 50 the wheel, in combination with an additional member joined to the first named member, such members respectively provided with apertures concentric to such axis, and a tongue forced out from one of such members 55 and arranged to connect the members adjacent to the concentric apertures.

3. In a printing wheel, a sheet metal member provided with a body portion, and provided with a plurality of lugs arranged in 60 planes which are concentric to the axis of the wheel, in combination with an additional member, provided with an annular flange having an aperture therethrough, joined to the first named member, such members re-

spectively provided with apertures concentric to such axis, and one of such members provided with a tongue forced out therefrom and arranged to connect the members adjacent to the concentric apertures. 65

4. In a printing wheel, a sheet metal member provided with a body portion and provided with a plurality of lugs respectively arranged in planes which are concentric to the axis of the wheel, in combination with an additional sheet metal member provided with a body portion and with a cylindrical portion, such cylindrical portion having an aperture therethrough, such members joined together so that the cylindrical portion of the last named member forms the periphery of the 70 wheel between the lugs of the first named member and the aperture in the cylindrical portion arranged to come between two of such lugs, and such members provided with apertures concentric with the axis of the 75 wheel.

5. In a printing wheel a sheet metal member provided with a body portion and provided with a plurality of lugs respectively arranged in planes which are concentric to the axis of the wheel, in combination with an additional sheet metal member provided with a body portion and with a cylindrical portion, such cylindrical portion having an aperture therethrough, such members joined together so that the cylindrical portion of the last named member forms the periphery of the 80 wheel between the lugs of the first named member and the aperture in the cylindrical portion arranged to come between two of such lugs, and such members provided with apertures concentric with the axis of the 85 wheel.

Having thus described my invention what I claim as new and desire to secure by Letters Patent is:—

35 1. In a printing wheel, a sheet metal member provided with a body portion, and provided with a plurality of lugs arranged in planes which are concentric to the axis of the wheel, in combination with an 40 additional member joined to the first named member, said additional member provided with an annular flange having an aperture therethrough, said members respectively provided with apertures concentric with the axis of the wheel, and one of such members provided with a tongue forced out therefrom and arranged to connect the members 45 adjacent to the concentric apertures.

2. In a printing wheel, a sheet metal member provided with a body portion, and provided with a plurality of lugs arranged in planes which are at right angles to the body portion of such member, and the other member of the device provided with a portion thereof forced into a cylindrical shape and arranged to fit closely between the lugs of the first named member, such cylindrically shaped portion provided with an aperture, and both such members provided with a central aperture, and one of such members provided with a tongue forced out from the body portion thereof and arranged to form a connection between the members adjacent to the central apertures. 50

3. In a printing wheel, a sheet metal member provided with a body portion, and provided with a plurality of lugs arranged in planes which are concentric to the axis of the wheel, in combination with an additional member, provided with an annular flange having an aperture therethrough, joined to the first named member, such members re- 55

6. A printing wheel, consisting of two members respectively made of sheet metal, one of such members provided with a plurality of lugs and raised characters on such lugs, and such lugs arranged in planes which are at right angles to the body portion of such member, and the other member of the device provided with a portion thereof forced into a cylindrical shape and arranged to fit closely between the lugs of the first named member, such cylindrically shaped portion provided with an aperture, and both such members provided with a central aperture, and one of such members provided with a tongue forced out from the body portion thereof and arranged to form a connection between the members adjacent to the central apertures. 115

7. A printing wheel, consisting of two 120 members respectively made of sheet metal, one of such members provided with a plurality of lugs and printing characters on

such lugs, said lugs arranged in planes which are at right angles to the body portion of said member, and the other member of the device provided with a portion thereof forced into a cylindrical shape and arranged to fit closely between the lugs of the first named member, such cylindrical portion

provided with an aperture, and both said members provided with a central aperture.

ISAAC S. DEMENT.

In the presence of—

CHARLES TURNER BROWN,
CORA A. ADAMS.
